UNITED STATES PATENT OFFICE.

THURBUR F. RUSSELL, OF NEWTON, MASSACHUSETTS.

PAPER-FASTENING DEVICE.

SPECIFICATION forming part of Letters Patent No. 767,444, dated August 16, 1904.

Application filed October 1, 1902. Serial No. 125,458. (No model.)

To all whom it may concern:

Be it known that I, THURBUR F. RUSSELL, of Newton, county of Middlesex, and State of Massachusetts, have invented an Improvement 5 in Paper-Fastening Devices, of which the following description, in connection with the accompanying drawings, is a specification, like letters on the drawings representing like parts.

The present invention relates to a paper- 10 fastening device, and is embodied in a machine for fastening together sheets of paper and the like, the object of the invention being to obtain an efficient and durable machine for this purpose which is simple in construction 15 and easily operated. The machine embodying the invention is so arranged that two movements of an actuating device will result in punching the sheets of paper to be fastened and subsequently inserting in the punched 20 opening a suitable fastening device, the machine being especially adapted to be used with eyelets of the kind commonly employed in shoe-uppers and frequently used for fastening papers. The machine is entirely auto- 25 matic in its operation, comprising a support for the papers to be fastened, a punch and setting device, an automatic feed for the fasteners, and a single actuator adapted to cause the machine to perform the complete opera- 30 tion of punching the papers and feeding and setting the fastening device.

The invention is herein shown as embodied in a machine adapted to utilize eyelets for fastening devices, and comprises a punching- 35 die and its coöperating member and a setting device and its coöperating member, both of which are mounted on a reciprocating carriage which is adapted to move back and forth relatively to a stationary support for the 40 papers.

The punch and setting device are provided with a common actuating member adapted by its movement in one direction to cause the operation of the punch and by its movement in 45 the opposite direction to cause the operation of the setting device, the said actuating member being also connected with the carrier for the punch and setting device, so as to move the said carrier between the successive 50 operations of the punch and setting device to

remove the punch from its operating position and to bring the setting device to the same position, so as to be in alinement with the hole or perforation made in the papers by the punch. Coöperating with the setting de- 55 vice is a feed member to supply fastening devices to the setting device, so that at the time when said setting device is moved to its operative position it has already been supplied with a fastening device to be set in the previously-punched hole in the papers. As herein shown, the lower member of the setting device is provided with a pin or support which is arranged to be held flush with the lower setting member during the movement of said 60 member toward a suitable feed-chute, which is supplied with eyelets and which has at its lower end a yielding stop for the eyelets, the said pin being arranged to move upward and engage an eyelet at the time when said lower 65 member is below the chute. In the reciprocating movement of the carrier for the punch and setting device after the hole has been punched in the papers the eyelet is carried along upon the pin, so as to be presented to 70 the punched opening, and in the setting operation the pin is depressed and retained in its depressed position until it again reaches 75 the chute ready to pick up an eyelet.

The machine is further provided with a re- 80 taining device to hold the papers in position during the punching and setting operation, the said retaining device being so arranged as to move into contact with the papers in re- 85 sponse to the first movement of the actuating device which produces the punching operation and to remain in engagement with the papers during the subsequent operation of the machine, being finally released after the pa- 90 pers have been fastened.

Figure 1 is a side elevation of a machine embodying the invention; Fig. 2, a partial front elevation of the same, partly in section; Fig. 3, a transverse vertical section; Fig. 4, a partial underneath plan view. Fig. 5 is a lon- 95 gitudinal section showing the parts of the machine during the punching operation, and Fig. 6 is a similar view showing the parts of the machine at the end of the setting operation.

Referring to Fig. 5, the punch *a* and upper 100

setting device b are mounted so as to be longitudinally movable in a reciprocating carriage c , which is adapted to slide upon the bed or frame A of the machine, the said carriage 5 having wings c^2 , Figs. 2 and 3, which are held in position by means of plates A^2 , which are secured to the frame so as to overlie the said wings and to afford lateral guides for a portion of the carriage above the said wings. 10 The punch a is shown as a plunger fitting a vertical opening in the carriage c and having a shoulder a^2 , between which and the bottom of the opening is interposed a spring a^3 , which tends to hold the punch in the position 15 shown in Figs. 1 and 6. The said punch is provided with a cutting-die a^4 , which is adapted to enter a corresponding female die a^5 in the body portion of the carriage c , so that when the said punch a is depressed with 20 sheets of paper between it and the die a^5 it will punch a hole for the reception of a suitable fastening device. The setting-die b is also arranged to coöperate with a corresponding member b^2 , which supports the rim of the 25 eyelet while the shank is being crushed into engagement with the papers to be fastened. The carriage c is arranged to be reciprocated through the action of a lever d , which is pivotally supported at d^2 and provided with a 30 slot d^3 , which engages a pin or projection c^3 from the carriage c , so that when the said lever d is swung upon its pivot d^2 it will cause the carriage c to move back and forth along the frame A , upon which it is supported. 35 The said lever d is shown as arranged to be actuated by means of a cam-groove e , formed in a member e^2 , which is shown as a plate suitably secured upon an oscillating shaft f , to which is also secured the actuating-handle g . 40 The same actuating-handle is arranged to co-operate also with the punch a and the upper setting device b and has a considerable range of movement, the cam-groove e , therefore, being shaped so as to produce no movement 45 of the cam-roll d^4 and the lever d during a greater part of its throw, the said movement taking place at about the middle of the complete movement of the handle g , as shown in the drawings. 50 Starting, for example, from the position shown in Fig. 1 and moving the actuator g to the position shown in Fig. 5, the cam-roll d^4 will remain in the portion e^3 of the cam-groove cut in the member e^2 , the said portion being 55 curved on an arc struck from the center of movement of said member e^2 , so that no movement of the reciprocating carriage c will take place during this movement of the actuator g . The carriage c is thus held in the position 60 shown in Fig. 5, in which the punch members a^4 and a^5 are in position to punch a hole in the paper, and during this time the punching member a is acted upon by a cam g^2 , formed on the actuating member g , the said cam bearing directly upon the top of the punch a , so 65 as to force the same downward and punch the paper. The actuator g is then turned in the opposite direction, and the punch a , being released by the cam g^2 , rises through the action of the spring a^3 , the cam-roll d^4 reaching the 70 portion e^4 of the cam-groove in the member e^2 at about the time when the punch has reached its normal position. The action of the cam-groove at this period in the operation is to swing the lever d upon its pivot d^2 and move the carriage c to the left, thus bringing the setting members b and b^2 into the position 75 previously occupied by the punching members, so that they are in alinement with the hole made by the punch, the papers not having been moved in the meanwhile. A continued movement of the actuating member g to the right as indicated in Fig. 6 will produce no further movement of the carriage c , since the portion e^5 of the cam-groove e is also 80 curved on an arc struck from the center of oscillation of the supporting member f . Such movement, however, is communicated to the upper setting member b through the agency of a link b^3 , which is pivotally connected at b^4 85 to the upper end of the setting member b , the said link b^3 being operated upon in turn by a pin g^3 , which enters a slot b^5 in the link b^3 , engaging the bottom of said slot and depressing the link and setting device b as the actuating member g is pushed over to the position shown 90 in Fig. 6. The lower setting device b^2 having been previously provided with a fastening device, such as an eyelet, thus presents the eyelet to the opening and the eyelet is 95 clenched, as shown in Fig. 6. Upon restoring the handle g to its intermediate position the setting devices are separated from each other and the papers, properly fastened, may be removed. 100

In order to supply the lower setting device b^2 with the fastening devices, the machine is shown as provided with a feed-chute h , leading from a suitable hopper h^2 , which is adapted to contain a mass of eyelets, which travel down the chute, the lowermost eyelet being held in the end of the chute by means of the ordinary spring-gate or yielding member, which prevents the eyelet from falling from the chute through its own gravity, but permits the eyelet to be pulled from the chute if extraneously engaged. To engage and feed the lowermost eyelet, the lower setting device b^2 is shown as provided with a depressible finger b^6 , which is normally pressed upward by 110 means of a spring b^7 , but arranged to be engaged by a suitable retaining device after it has been depressed during the operation of setting the eyelet. 115

As herein shown, the finger b^6 is provided at its lower end with a tapered projection b^8 , above which is a shoulder b^9 , the said tapered projection being arranged to engage a slot which is formed between two separable members k , secured to the under side of the frame 120 130

A by means of screws k^2 and normally held together by means of springs k^3 , said members, however, having slots k^4 (dotted lines, Fig. 4) whereby they may be moved laterally to separate them. The said members are cut to form a slot between them substantially equal in width to the diameter of the finger b^6 , but smaller than the diameter of the shoulder b^9 , so that when the said finger b^6 is forced downward by the upper set, as shown in Figs. 3, 4, and 6, the tapered member b^8 will push through, separating the members k , which will spring together after the shoulder b^9 has passed below the said members k , which members then constitute a retaining device to prevent the upward movement of the finger. The slot for the said finger b^6 extends along the members k in the direction of movement of the carriage c , and at the point where the said finger reaches the feed-chute h the said slot is widened so as to afford space sufficient to permit the passage of the shoulder b^9 , thus permitting the upward movement of the finger b^6 in response to the action of the spring b^7 . The finger b^6 then being below the end of the chute h , it is obvious that the finger will enter an eyelet in said chute and engage the same, so that it will carry away the said eyelet during the next reciprocating movement of the carriage c , properly presenting the same to the upper setting device b , which is then in the position to complete the setting operation.

During the fastening operation the paper is supported upon a table m , which is shown as a frame having a large middle opening for the operation of the fastening devices, the said table being supported upon the frame A by means of studs m^2 at opposite sides of the machine. The paper is held in position by means of a retaining device, which is shown as mounted on a rock-shaft n , having bearings n^2 upon the table m , the said rock-shaft being provided with a spiral spring n^3 , the tendency of which is to hold the same in the position shown in Fig. 1. The paper is retained in position by means of spring-fingers n^4 , connected with the said rock-shaft n and arranged to be moved toward the surface of the table m , so as to hold the paper thereon. These fingers normally stand away from the table, as shown in Fig. 1, and the carriage c is also provided with a guide member c^4 , which, in conjunction with the table m , tends to hold the loose sheets of paper together until the said sheets are engaged by the fingers n^4 . The said fingers are arranged to be pressed downward upon the surface of the papers during the first movement of the actuating-handle g , which produces the operation of the punch a , this being accomplished by means of an actuating member o , shown as pivotally supported upon the side of the carriage c and arranged to be acted upon by a cam-surface e^6 , formed on the member e^2 , and in turn to act upon a radi-

ally-projecting member n^5 , secured to the rock-shaft n . This cam o normally stands in the position shown in Fig. 1, being limited in its movement by a stop o^2 ; but in the first movement of the actuating member g to the left the said cam is engaged by a projection e^7 , formed on the cam-surface e^6 , which turns it toward the right, causing it to act upon the arm n^5 and force the fingers n^4 down toward the paper supported upon the table m . The member o will remain in this position during the subsequent operations of punching the paper and shifting the carriage, but will be restored to its normal position during the setting operation, in which the cam-surface e^6 strikes the member o and moves it back into its normal position.

I claim—

1. In a paper-fastening machine, a punch and anvil; a setting device comprising upper and lower members; means for supplying a fastener to one member of said setting device; an oscillating member provided with means for operating the punch by a movement in one direction and the setting device by a movement in the other direction; a reciprocating carriage for said punch and setting device; and a cam carried by said oscillating member for reciprocating said carriage to shift the positions of the devices between operations thereof, said oscillating member thus constituting a common actuating device for all of said parts.

2. In a paper-fastening machine, a punch; a setting device for the fasteners having two members; a reciprocating carriage for said punch and setting device; an actuating member movable in one direction to operate the punch and in the other direction to operate the setting device; means connected with said actuating member for reciprocating the carriage between the operation of the setting device and that of the punch; and means for supplying the setting device with a fastener.

3. In a paper-fastening machine, a reciprocating member provided with a punch and die and an upper and lower setting device; a finger movable through the lower setting device and arranged to be depressed during the setting operation; means for retaining said finger depressed during that movement of the carriage which brings the punching members into operating position; an eyelet-feed chute extending over said carriage; means for releasing said finger when in alignment with the end of said feed-chute; and an actuating device for the punch, setting device, and carriage.

4. In a paper-fastening machine, the combination with a support for the papers; of a retaining device for holding the papers on said support during the operation of punching a hole and setting a fastener therein; a punch and a setting device having upper and lower members; a reciprocating carriage for said

- punch and setting device; an oscillating member provided with means for operating said punch by a movement in one direction, and said setting device by a movement in the other 5 direction, and also with means for reciprocating said carriage between such operations; an operating member for the retaining device for the papers; and means connected with the oscillating member to act upon said operating 10 member for the retaining device, as set forth.
5. In a machine for setting eyelets, a punch; a setting device having two members; a reciprocating carriage for said punch and both members of said setting device whereby the said 15 members are moved into the previous position of the punch after the material has been punched; an actuating member adapted by its movement in one direction to operate the punch and by its movement in the opposite 20 direction to operate the setting device; a cam carried by said actuating member for producing the reciprocating movement of the carriage; and means for supplying the setting device with eyelets.
- 25 6. In a paper-fastening machine, a support for the papers to be fastened; a retaining device to hold the papers on said support; a punch; a setting device; a reciprocating carriage containing said punch and setting device; a lever connected with said carriage; an actuating member provided with means for 30 operating the punch by a movement in one direction, and said setting device by a move-

ment in the other direction and also with a cam-groove coöoperating with said lever to reciprocate the carriage between such successive operations; and cam projections carried by said actuating member to cause the retaining device to engage the papers at the beginning of the operation and to release the papers 40 at the end thereof.

7. In a machine for setting eyelets, a reciprocating carrier containing a punch and anvil and the two members of a setting device; means for reciprocating said carriage; means for alternately operating the punch and setting device; a spring-finger in one member of the setting device; a shoulder formed on said spring-finger and a tapered portion beyond said shoulder; two separable members between 50 which said tapered portion is forced in the setting operation, said members coöperating with said shoulder to prevent the outward movement of the spring-finger during the movement of the carriage; a stationary eyelet-chute; and 55 an opening between the separable members adjacent to the end of the eyelet-chute large enough to permit said shoulder to pass through.

In testimony whereof I have signed my name to this specification in the presence of two subscribing witnesses.

THURBUR F. RUSSELL.
